ATTORNEYS

UNITED STATES PATENT OFFICE.

WILLIAM E. KIDDER, OF KALAMAZOO, MICHIGAN.

CHAIR.

Application filed March 4, 1922. Serial No. 540,993.

To all whom it may concern:

Be it known that I, WILLIAM E. KIDDER, a citizen of the United States, residing at the city and county of Kalamazoo, State of Michigan, have invented certain new and useful Improvements in Chairs, of which the following is a specification.

This invention relates to improvements in chairs.

10 The main object of this invention is to provide an improved chair seat or back particularly adapted for use on folding chairs which is light in weight and permits the use of inexpensive materials and at the same time is very strong and durable.

Further objects, and objects relating to structural details, will definitely appear from the detailed description to follow.

20 I accomplish the objects of my invention by the devices and means described in the following specification. The invention is clearly defined and pointed out in the claims.

25 A structure which is a preferred embodiment of my invention is clearly illustrated in the accompanying drawing, forming a part of this application, in which:

30 Fig. I is a front perspective view of a folding chair embodying the features of my invention.

Fig. II is a vertical transverse section through the seat on a line corresponding to line 2—2 of Fig. I.

35 Fig. II^A is a vertical section from front to rear on a line corresponding to line 2^A—2^A of Fig. II.

40 Fig. III is a front perspective view of another embodiment of my invention, the lower portion of the chair being broken away.

Fig. IV is a transverse section on a line corresponding to line 4—4 of Fig. III, showing structural details.

45 In the drawing similar reference characters refer to similar parts throughout the several views, and the sectional views are taken looking in the direction of the little arrows at the ends of the section lines.

50 Referring to the drawing, the legs 1 and 2 are pivoted at 3 to be collapsed. The legs 1 are extended into side bars 4 supporting the back, designated generally by the numeral 5. The seat, designated generally by the numeral 6, is pivoted to the upper ends of the legs 2 and is connected to the legs 1 to permit the folding of the legs.

These features form no part of this invention and are, therefore, not detailed herein.

The seat 6 comprises a rectangular frame made up of a front member 7, rear member 8 and side members 9. The front and rear members have opposed grooves 10 in their inner edges in which the ends of the bottom filling 11 are loosely arranged. This bottom filling is supported by the centrally disposed cross rod 12 having its ends disposed in bores 13 in the side pieces 9 of the frame so that the filling is centrally supported without interfering with independent movement. The rod 12 is formed of wire so that it may yield slightly under pressure and also so that the frame members are not materially weakened by the bores 13 into which the ends of the rod project. With this arrangement the filling 11 may be made of comparatively poor or brash material and at the same time is effectively supported by the rod so that there is very little danger of breakage in use.

55 In the embodiment of my improvements shown in Figs. III and IV the seat frame members are all provided with grooves 14 on their inner edges and bottom panel 15 of fibre board or thin veneer is disposed with its edges in these grooves, the panel being supported by one or more of the rods 12. A pair of the rods is shown in Fig. III.

60 My improvements enable the employment of comparatively light material both in the frame and bottom of the seat or back and at the same time the structure is strong enough to support heavy loads and withstand severe strain.

65 I have illustrated my improvements in two embodiments which I have found very practical. I have not attempted to illustrate or describe other modifications or adaptations or to illustrate various types of chairs to which they are adapted as I believe the embodiments illustrated will enable those skilled in the art to which my invention relates to embody or adapt the same as may be desired.

70 Having thus described my invention, what I claim as new and desire to secure by Letters Patent, is:—

75 1. A chair seat or back comprising a rectangular frame provided with opposed side members having grooved inner edges and opposed side members having bores in their inner edges, a filling comprising a plurality

of slats having their ends loosely engaged in said grooves, and a resilient supporting rod disposed transversely below said slats with its ends loosely engaged in said bores and 5 yieldingly supporting said slats.

2. A chair seat or back comprising a frame provided with opposed members having grooved inner edges, and opposed members having opposed bores in their inner

edges, a filling having its ends loosely engaged in said grooves, and a resilient supporting rod disposed below said filling with its ends loosely engaged in said bores and yieldingly supporting said filling. 10

In witness whereof, I have hereunto set 15
my hand and seal.

WILLIAM E. KIDDER. [L. s.]
